CONTAINER DISPLAY TOP

Valentine George Faulhafer, Vancouver, British Columbia, Canada

Application February 13, 1934, Serial No. 711,016
In Canada March 7, 1933

4 Claims. (Cl. 217—58)

My invention relates to container display tops and the principal object is to provide a top for wooden fruit boxes such as generally contain apples, oranges, etc.

5 A further object of my invention is the provision of a top for containers which will permit the inspection of the contents of said container without permitting the removal of the contents.

10 A still further object of my invention is the provision of a container top which may be quickly put on and removed from the container so that the top may be used over and over again with other containers.

15 These and other objects will be more fully explained in the following specification and accompanying drawing considered together or separately.

In the drawing:

20 Figure 1 is an isometric view of the container top.

Figure 2 is a side view of the container top.

Figure 3 is a front view of the container top showing 1 attached to a container.

25 Similar characters and numerals of reference refer to similar parts thereon in the several views.

30 The numeral 1 designates one of the side pieces of the top to which is riveted by means of the rivets 5 a number of metallic slats 4 as shown more particularly in Figure 1 with the other end 35 of the slats 4 being riveted at 5 to the end piece 6. The distance between the end pieces 1 and 6 corresponds to the outside width of the container to which the top is to be attached, being placed over top of said container as clearly illustrated in Figure 3.

40 In order to clamp the container and to prevent the top from being removed therefrom, the side piece 1 is provided with a series of prongs 8, the points of which are disposed in a direction to engage and penetrate a wall of a box when engaged therewith, and I further provide a lever 10 centrally pivoted at 9 at the middle of the end piece 6. To diametrically opposite sides of the lever 10 are attached rods 11, each rod terminating into a hook 13. The wires 11 extend 45 through sleeves 12 so as to provide a bearing support therefor, and as may be readily seen in Fig. 2, the hooks 13 extend beyond respective edges of the end piece 6, so as to readily admit a box therebetween. As shown in the position in

50 Figure 2, the hooks 13 are in an inoperative condition, allowing the top to be removed from the container. When the lever 10 is swung over to one side as shown in the dotted lines, the hooks 13 are drawn toward each other and grasp the 55 sides of the wooden box so that in conjunction with the prongs 8 the top cannot be removed, although the contents of the container are perfectly visible and present an attractive appearance enabling the purchaser to see and examine 60 the fruit which he is about to buy.

In accordance with the provisions of the patent statutes, I have described the principle of my invention, together with the apparatus which I now consider to represent the best embodiment thereof; but I desire to have it understood that the apparatus shown is merely illustrative and that the invention can be carried out in other ways.

Having thus described my invention, I claim:

1. A box attachment comprising a pair of box-engaging members having angularly disposed walls, spaced slats connected to a wall of each of the box-engaging members, one of the box-engaging members having prongs formed in one of the angularly disposed walls for engagement with a box, said other box-engaging-member having bearing members, rods slidably mounted in said bearing members, said rods having hook portions positioned exteriorly of the box-engaging member and adapted to engage portions of a box, and means associated with the rods for moving the hook portions into and out of engagement with a box.

2. A box attachment comprising a pair of opposed box-engaging members, spaced slats connected to respective members, one of said members having prongs adapted to engage a portion of a box disposed between the members, a pair of oppositely disposed rod members slidably supported by the other member, a lever pivotally mounted upon the last named member, said rod members being pivotally engaged with the lever and having hook portions at their free ends adapted to be drawn into engagement with a box upon movement of the lever in one direction.

3. A box attachment comprising a pair of opposed box-engaging members, spaced slats connected to respective members, one of said members having prongs adapted to engage a portion of a box disposed between the members, a pair of oppositely disposed rod members slidably supported by the other member, each of said rods having hook portions at their free ends adapted to be drawn into engagement with a box, and lever means associated with the rods for moving and holding the hooks in engagement with a box.

4. A box attachment comprising a pair of box-engaging members having angularly disposed walls, spaced slats connected to a wall of each of the box-engaging members, one of said members having a pair of oppositely disposed slidable rods, a lever pivotally mounted upon said last named member, said rods being pivotally engaged with the lever and having hook portions at their free ends adapted to be drawn into engagement with a box upon movement of the lever in one direction, and box-attaching means upon the other of said box engaging members.
